UNITED STATES PATENT OFFICE

90,838

DESIGN FOR A BAG OR ANALOGOUS ARTICLE

Henry Walter Dittmann, North Bergen, N. J., assignor to Standard Brands Incorporated, New York, N. Y., a corporation of Delaware

Application August 8, 1933. Serial No. 48,968

Term of patent 14 years

To all whom it may concern:

Be it known that I, HENRY WALTER DITTMANN, a citizen of the United States, residing at 1195 Fifth Avenue, North Bergen, New Jersey, have invented a new, original and ornamental Design for a Bag or Analogous Article, of which the following is a specification, reference being had to the accompanying drawing, forming part thereof.

The different varieties of linings on the drawing are indicative of contrasting colors.

I claim:

The ornamental design for a bag or analogous article, as shown and described.

HENRY WALTER DITTMANN.
